PLASTIC UMBRELLA FRAME
CONSTRUCTION

Sol Isler, New York, N. Y.

Application May 22, 1944, Serial No. 536,772

3 Claims. (Cl. 135—29)

This invention relates to the construction of umbrella frames in which plastic is substituted in whole or in part for metal, which is usually employed.

The principal object of the invention is to make the rib elements in the form of plastic rods, and to modify the articulated portions of the frame to adapt them to receive the plastic elements.

Other objects of the invention will appear as the following description of preferred and practical embodiments proceed.

In the drawing which accompanies and forms a part of the following specification and throughout the several figures of which the same reference characters have been used to denote identical parts:

Figure 1 is a vertical substantially diametrical section through an open umbrella, showing a frame embodying the principles of the invention;

Figure 2 is a fragmentary sectional view showing details of construction;

Figure 3 is a horizontal section taken along the line 3—3 of Figure 1;

Figure 4 is a vertical section showing a modified form of the invention.

Referring now in detail to the several figures, and advertiring first to that form of the invention shown in Figures 1, 2 and 3, it is apparent from Figure 1 that the general arrangement of the frame structure is that of the conventional umbrella frame, in that it has a series of radiating canopy ribs for spreading and tensioning the cover, hingedly connected to an upper ferrule fixed to the shaft, a series of corresponding radiating stretchers hingedly connected to a sliding ferrule on the shaft and to the canopy ribs at intermediate points.

The present invention substitutes for the conventional all-metal ribs and stretchers, a composite structure in which the ribs and stretchers have the form of plastic rods with attached metal ends forming hinge connectors with the respective ferrules, and with intermediate connectors carried by the canopy ribs.

The umbrella frame shown in Figures 1, 2 and 3 comprises a shaft 1, having the upper fixed ferrule 2 and the lower slidable ferrule 3. Said ferrules may be of known construction identically expanded adjacent their upper ends into the respective collars 4 and 5, one of which is shown in Figure 3, said collars being radially slotted, as shown at 6 in Figure 3, and each having a deep circumferential slot 7 opening in the periphery thereof and intersecting the slots 6 to receive the

wire which secures the canopy ribs and supporting ribs hingedly to the respective ferrules.

The canopy ribs, as shown, each comprises a plastic rod 8, which may be extruded or molded, and is preferably of uniform cross-section throughout its length. Each canopy rib 8 is attached at its inner end to a preferably metallic connector 9, the same being hingedly connected to the ferrule 2. As shown in Figure 2, the connector 9 has a flattened perforated inner end 10, through the perforation of which the hinge wire 11 passes, the opposite end of the connector comprising a threaded extension 12 of reduced diameter, which screws into a threaded socket 13 at the inner end of the plastic rib 8. Preferably, but not necessarily, the screw connection between the rib and connector is supplemented by cement.

The canopy ribs 8 are provided at an intermediate point in their length with a connector 12', which takes the place of the conventional clamp connector associated with the all metal rib. The connector 12' is preferably of metal; comprises a tubular base portion 13, adapted to be slipped upon the rib 8, and to be cemented in place. The intermediate connector 12' has a perforated bifurcated lug 14.

The stretchers 15 are formed as plastic rods with threaded socketed opposite ends 16 adapted to receive the end connectors 17 and 18, which may be identical with the end connectors 9. The flat ends of the connectors 17 and 18 lie respectively between the bifurcations of the lug 14 and within the radial slots of the collar 5 of the ferrule 3. The wire 19 secures the connectors 18 to the lower ferrule, while the connectors 17 are hingedly secured to the intermediate connectors 12' by suitable pivot pins 20.

Instead of the end connectors having threaded extensions extending into the socket ends of the plastic ribs, as shown in Figures 1, 2 and 3, said end connectors may be in the form of sockets, as shown at 21 in Figure 4, receiving the ends of the plastic ribs.

Since it is contemplated that the end connectors, the intermediate connectors 12', and the ferrules shall be of metal, the ferrules and the associated connectors may be preassembled as units, before the plastic ribs are thereto attached, and this is true also of the intermediate connectors and the associated end connectors of the supporting ribs.

It is within the purview of the invention, when suitable plastics are developed, to make the fer-

rules and connectors or any part of them, of plastic, instead of metal, if desired.

In that form of the invention shown in Figures 1, 2 and 3, in the interest of simplification of the manufacture of the plastic ribs 8 and 15, they are shown as being cylindrical in form, and without any differentiating integral plastic structure throughout their extent. Consequently, the free ends of the canopy ribs 8, as shown, are imperforate and cylindrical in form. Each panel of the cover 21' is provided at its end with a socketed tip 22, which by tensioning the cover may be slipped over the ends of the plastic ribs. It is optional whether the tips 22 be made of plastic or metal, or whether they shall freely engage the ends of the canopy ribs or be cemented or otherwise secured thereto.

In that form of the invention shown in Figure 4, the intermediate connector 23 is formed with a discontinuous bore, forming sockets 24 and 25 at its opposite ends, and the plastic canopy rib is in two sections, having their adjacent ends inserted and secured in the respective sockets. The end connectors 26, 27 and 28, as shown, are provided with sockets receiving the adjacent ends of the respective ribs.

For convenience in replacing a broken stretcher 28, the opposite ends of the stretcher may be formed, respectively, with a right and left thread, so that after removal of the broken stretcher a replacement stretcher can be readily screwed into position.

While in the above description I have disclosed what I believe to be preferred and practical em-

bodiments of the invention, it will be understood by those skilled in the art that the specific details of construction and arrangement of parts, as shown and described, are by way of illustration and not to be construed as limiting the scope of the invention defined in the appended claims.

What I claim as my invention is:

1. Composite rib construction for umbrella frames comprising plastic rib sections and a connector consisting of a sleeve having sockets at its opposite ends receiving the adjacent ends of said rib sections, and a lug carried by said sleeve adapted to be pivotally interconnected with a stretcher.
- 15 2. Composite rib construction for umbrella frames comprising plastic rib sections, an intermediate connector consisting of a sleeve having sockets at its opposite ends receiving the adjacent ends of said rib sections and an end connector having a socket receiving the other end of one of said rib sections, said connectors each including a perforated lug adapted to be hingedly connected respectively with a stretcher and a fixed ferrule.
- 20 3. In an umbrella frame construction, a stretcher member adapted to be pivotally connected at its ends respectively to a sliding ferrule and to the intermediate connector of a canopy rim, said stretcher member comprising end connectors and an intermediate stretcher having right and left threaded connections with the respective end connectors.

SOL ISLER.
